FILLING MACHINE

Robert J. Aul, Toledo, and Folke Malcolm Gustafson,
Maumee, Ohio, assignors to The Multi-Fill Machine
Company, Toledo, Ohio, a corporation of Ohio

Application September 11, 1959, Serial No. 57,519

Term of patent 14 years

(Cl. D55—1)

FIG. 1.

Des. 187,434

PAGE 2

FIG.2.

FIG.3.

FIG. 4

Fig. 1 is a view in front perspective of a filling machine showing my new design;

Fig. 2 is a plan view of the machine shown in Fig. 1;

Fig. 3 is a view in front elevation, and

Fig. 4 is an end view in elevation, the opposite end not disclosed being substantially the same.

We claim:

The ornamental design for a filling machine, substantially as shown and described.
